COMBINATION HIGH- AND LOW-PRESSURE HYDRAULIC PUMP

Carl T. Swanson, Quonset Point, R. I.

Application February 19, 1945, Serial No. 578,757

3 Claims. (Cl. 103—37)

(Granted under the act of March 3, 1883, as amended April 30, 1928; 370 O. G. 757)

1

This invention relates to a hydraulic pump and has for an object to provide a hydraulic pump which may be used for supplying either low or high pressure as may be needed and which will automatically supply high pressure instead of low pressure when the high pressure is needed to overcome the resistance.

A further object of this invention is to provide a hydraulic pump which will supply low pressure until the resistance thereto becomes as great as the low pressure, whereupon the pump will automatically supply high pressure.

Still a further object of this invention is to provide a pump that may be manually operated for supplying fluid pressure, which pressure will shift automatically from low pressure to high pressure as the resistance increases to such an amount that it may be only overcome by high pressure.

With the foregoing and other objects in view, the invention consists in the construction, combination and arrangement of parts hereinafter set forth, claimed and illustrated in the drawing in which, the figure is a partly sectional, partly detailed, elevational view of the hydraulic high and low pressure pump of this invention.

The hydraulic pump of this invention includes a main cylinder 11 having inlet and outlet valves 12 and 13 connecting the main cylinder chamber 14 by way of a passage 15 from an inlet fluid line 16 to an outlet pressure line 17. Threaded on the cylinder 11 is a cylinder cap 18 on which is mounted a flange plate 20 acting as a base for a lug 21 to which is pivoted a link 22, which link 22 in turn is pivoted at 23 to a pump arm 24 terminating in a pump handle 25.

Also pivoted to the pump arm 24 as at 26 is a second link 27 which is internally threaded for receiving the upper end of a piston rod 28. The piston rod extends through a bronze bushing 30 in the flange plate 20 and cylinder cap 18 into the main cylinder 11. Movable within the chamber 14 in the main cylinder 11 is a main piston 31 provided with a packing ring 32 for preventing the escape of pressure from chamber 14. Instead of being rigidly secured to the main piston 31, the connecting rod 28 is movably secured thereto by means of a coiled spring 33 located within a hollowed chamber 34 formed in the upper end of the main piston 31, the upper end of chamber 34 being closed by a nut 35 threaded into the end of chamber 34. The connecting rod 28 is provided with a circumferential ridge 36 within the chamber 34.

The lower end 37 of the connecting rod 28 ex-

2

tends through a cylindrical chamber 38 formed in the main cylinder 31 and the piston rod end 37 is provided with a packing ring 40 cooperating with the walls of the cylindrical chamber 38. The nut 35 is provided with a small vent 41 permitting the nut 35 to be assembled in position. A larger vent 42 is provided through the flanged plate 20 and cap 18 to the top of main cylinder 11 thereby permitting the main piston 31 to move in the main chamber 14 without compressing any air thereabove.

In operation, when the pump rod 24 is moved up and down manually by means of the pump handle 25, the double pivoted link 22 permits a straight vertical motion to be imparted to the connecting rod 28 and the main cylinder 31. Due to the coil spring 33, the connecting rod 28 transmits its motion to the main piston 31 pumping the fluid from the inlet line 16 and through inlet valve 12 to the outlet valve 13 and outlet pressure line 17 until the resistance in the line 17 becomes too great to continue moving the main cylinder 31 up and down within its chamber 14 in the main cylinder 11 and the operator then merely raises the handle 25 somewhat higher, thereupon compressing spring 33 and moving the end 37 of connecting rod 28 toward the top of cylindrical chamber 38, the vertical movement being limited by the piston rod ridge 36 abutting the completely compressed spring. He then reverses his motion to a down stroke, the coil spring 33 assisting in this down stroke. The ring packing 40 causes the end 37 of connecting rod 28 to act as a piston within the cylindrical chamber 38 and due to the small cross-section of the cylindrical chamber 38 and piston rod end 37, considerably higher pressure will be created by this motion than it is possible to create by the motion of the main piston 31, it being noted that the cross-sectional area of the cylindrical chamber 38 is approximately one-fourth that of the cross-section area of the main cylinder chamber 14. Obviously spring 33 could be omitted, and the back pressure alone could be relied on to hold piston 31 at the top of the cylinder while high pressure is being supplied. As a result thereof the operator first creates a low pressure in the main chamber 14 until the back pressure from pressure line 17 becomes too great, whereupon, by merely raising the pump handle somewhat higher the pump is automatically converted into a high pressure pump as he operates the piston-like end 37 of connecting rod 28 in the smaller cylindrical chamber 38, thus continuing the pumping at a much higher pressure against the resistance in the pressure line 17.

Other modifications and changes in the number and arrangement of the parts may be made by those skilled in the art without departing from the nature of this invention, within the scope of what is hereinafter claimed.

The invention herein described and claimed may be manufactured and used by or for the Government of the United States of America for governmental purposes without the payment of any royalties thereon or therefor.

What is claimed is:

1. A combination low pressure high pressure hydraulic pump comprising a main pump cylinder having fluid inlet and pressure outlet ports adjacent one end thereof, a pumping piston reciprocable within said main pump cylinder, a counterbored chamber extending through said piston with the small bore end toward said ports, a connecting rod reciprocably extending through said counterbored piston, one end of said connecting rod forming a pumping piston within the small bore of said counterbored chamber, means on said connecting rod within the large bore of said counterbored chamber yieldably securing said connecting rod to said piston, said yieldable securing means comprising a coil spring embracing said connecting rod, an abutment on said connecting rod within the large bore of said piston limiting the movement of said rod through the small bore of said piston, one end of said spring being based on said abutment, an apertured closure member for the other end of said large bore, the other end of said spring being based on said closure member, the other end of said connecting rod extending through said apertured closure member in the end of the large bore in said piston and the end of said main pump cylinder and pump operating means connected to said extended end of said connecting rod.

2. A combination low pressure high pressure hydraulic pump comprising a main pump cylinder having fluid inlet and pressure outlet ports, a main pump piston movable within said main cylinder, a pump arm, a link pivotally connecting said pump arm relative to said main cylinder, a connecting rod connected to said pump arm, a small cylindrical chamber in said main piston, an end of said piston rod extending into said small piston rod chamber, yieldable means securing said connecting rod to said piston, said yieldable securing means comprising a coil spring embracing said connecting rod within a large cylindrical chamber therein, an abutment on said connecting rod within the large cylindrical chamber of said piston limiting the movement of said rod through the small cylindrical chamber of said piston, one end of said spring being based on said abutment, an apertured closure member for the other end of said large cylindrical chamber, the other end of said spring being based on said closure member, said yieldable means permitting said piston rod end to reciprocate within

said small piston rod chamber when said yielding means is compressed, whereby said pump may deliver low pressure when said main cylinder piston is reciprocated and may deliver high pressure when said main piston abuts one end of its cylinder while said connecting rod is reciprocated within said small chamber in said piston rod against said yieldable connecting means.

3. A combination low pressure high pressure hydraulic pump comprising a main pump cylinder having fluid inlet and pressure outlet ports, a main pump piston movable within said main cylinder, a pump arm, a link pivotally connecting said pump arm relative to said main cylinder, a connecting rod connected to said pump arm, a small cylindrical chamber in said main piston, an end of said piston rod extending into said small piston rod chamber, yieldable means securing said connecting rod to said piston, said yieldable securing means comprising a coil spring embracing said connecting rod within a large cylindrical chamber therein, an abutment on said connecting rod within the large cylindrical chamber of said piston limiting the movement of said rod through the small cylindrical chamber of said piston, one end of said spring being based on said abutment, an apertured closure member for the other end of said large cylindrical chamber, the other end of said spring being based on said closure member, said yieldable means permitting said piston rod end to reciprocate within said small piston rod chamber when said yielding means is compressed, whereby said pump may deliver low pressure when said main cylinder piston is reciprocated and may deliver high pressure when said main piston abuts one end of its cylinder while said connecting rod is reciprocated within said small chamber in said piston rod against said yieldable connecting means, said main piston having a packing preventing leakage between said piston and the wall of said main cylinder, said piston-like end of said connecting rod within said small piston chamber being provided with a packing to prevent leakage therethrough.
